UNITED STATES PATENT OFFICE.

JACOB FRANKLIN FREDERICK, OF CHICAGO, ILLINOIS.

ATTACHMENT FOR PRINTING PRESSES.

1,414,871.

Specification of Letters Patent.

Patented May 2, 1922.

Application filed April 3, 1920. Serial No. 371,073.

To all whom it may concern:

Be it known that I, JACOB F. FREDERICK, a citizen of the United States, residing at Chicago, in the county of Cook and State 5 of Illinois, have invented new and useful Improvements in Attachments for Printing Presses, of which the following is a specification.

This invention relates to an attachment 10 for a printing press and has for its primary object the construction of an apparatus whereby a suction action may be created at required points to assure proper engagement between the traveling sheets and tapes, 15 and besides, the proper association of the various sheets upon the jogger board.

An object of the invention is to provide means for creating the suction for accomplishing the foregoing result and to use a 20 portion of the exhaust air to cool the ink rolls, which in practice are subject to excessive heating action which shortens the life of the rolls.

A feature of my invention is the novel 25 manner of constructing and associating the parts so that, in an inexpensive manner, I have been able to create a suction for holding the sheets in their proper position, and besides to cool the ink rolls and support the 30 gas burner in its most advantageous position.

With these and other objects in view the invention will be better understood from the following detailed description taken in connection with the accompanying drawing 35 wherein:

Fig. 1 is a diagrammatic view illustrating my invention in applied position.

Fig. 2 is a top plan view of the casing 40 with the nozzles connected thereto.

Fig. 3 is an end elevation of the casing.

Fig. 4 is a sectional view through the spray device.

Fig. 5 is a sectional view through the 45 exhaust pipe of the fan.

Figs. 6 and 7 are sectional views through one of the nozzles.

Again referring to the drawing illustrating my invention in a diagrammatic manner 50 the numeral 1 designates a casing completely enclosed and of a shape to be received between the traveling tapes 2. One wall of the casing is provided with a groove 3 for receiving the fly rest 4 while the other 55 end is provided with a plurality of hooks

5 for engagement over the delivery arm of the press. From this construction it will be seen that the casing may be very readily connected to the press and properly associated with the traveling tapes. The entire 60 upper surface of the casing is provided with a plurality of air-intake holes 6 decreasing in size toward the delivery arm of the press. Adjacent the groove 3 the casing is further provided with the holes 7 to increase the 65 efficiency of the attachment. Arranged on the table A beneath the fly 6 and around the jogger board C of the press, at the most advantageous points, is a plurality of nozzles 8 of any suitable construction, but for the 70 purpose of illustration shown as consisting of an open front boxlike casing 9, communicating with the interior of the casing 1 by the tube 10.

In a diagrammatic manner I have illustrated 75 a suction device in the form of a fan 11, the intake conduit 12 of which communicates with the interior of the casing 1 while the exhaust conduit 13 may have its outlet end arranged at any suitable 80 point.

As far as I have proceeded it will be seen that upon operation of the fan 11, the reduction of air pressure within the casing causes air to be sucked through the holes 85 6 and 7 and thus the suction action is relied upon to cause the air currents created to act on the traveling sheets in a manner to effectively hold them in engagement with the tapes and thus they are prevented from becoming 90 dislocated from their proper position. Simultaneously with this action air is sucked from the jogger board into the nozzles 8 which action causes the air currents created to force the sheets into their 95 proper relation upon the jogger board and thereby dispense with the services of an attendant to properly arrange the sheets. It is, of course, to be understood that this action may be accomplished in various other 100 manners than illustrated as the drawings are prepared in a diagrammatic manner to simplify the operation.

In practice it is advantageous to cool the ink rolls so as to prolong the life thereof 105 and to accomplish this I have shown means for discharging a portion of the exhaust air on to the rolls. This means consists of a plurality of spray holes 14 in the bottom of the casing which communicate with the hood 110

15 that in turn is connected by a pipe 16 with the exhaust pipe 13. A valve 17 in the exhaust pipe 13 controls the flow of the exhaust air which has the effect of regulating the passage of this exhaust air through the pipe 16 and through the openings 14 on to the ink rolls.

To complete the invention I have illustrated a burner 18 supported by the casing.

10 From the foregoing description taken in connection with the accompanying drawings it will be apparent that, in a very inexpensive manner, I am able to provide an apparatus that will create air currents in a 15 direction to regulate the travel of the sheets, and besides, to subject the ink rolls to air currents for cooling the same.

As the apparatus may be constructed in various other manners and the parts associated in different relations I do not desire to be limited in any manner except as set forth in the claims hereunto appended.

Having thus described my invention what I claim is:

25 1. In combination with a printing press embodying a jogger board and a plurality of traveling tapes, of a casing shaped and constructed to be arranged between the moving tapes and provided with a plurality of 30 air intake holes, means tending to create a vacuum in the casing, and a plurality of nozzles arranged around the jogger board and communicating with said casing.

2. In combination with a printing press 35 embodying a jogger board and a plurality of traveling tapes, of a casing disposed between said tapes and provided with a plurality of openings, a plurality of nozzles arranged around said jogger board, tubes connecting said casing and said nozzles, and means for creating a suction in said casing and said nozzles.

3. In combination with a printing press 45 embodying a jogger board and a plurality of traveling tapes, of an air suction device arranged between said tapes, means for creating a suction in said device and a plurality of nozzles arranged around said jogger board and also connected to said suction means.

50 4. In combination with a printing press embodying a jogger board, a plurality of traveling tapes, and inking rollers located adjacent to said tapes, of an air suction device arranged between said tapes, means for 55 creating a suction in said device, an auxiliary suction device arranged around said

jogger board, and means receiving air from the suction means and directing the same upon said inking rolls.

5. In combination with a printing press 60 embodying a plurality of traveling tapes and inking rollers disposed adjacent thereto, of a substantially rectangular casing disposed between said tapes and provided with a plurality of air-intake openings, means 65 for creating a suction in said casing and means for discharging a portion of the air from said suction means upon said inking rolls.

6. In combination with a printing press 70 embodying a jogger board, a plurality of traveling tapes and inking rollers located adjacent to said tapes, of a casing disposed between said tapes and provided with a plurality of openings in the top and in one end 75 thereof, means for creating a suction in said casing, means associated with the suction means for discharging air upon said inking rollers, and nozzles arranged around the jogger board and communicating with said 80 casing.

7. In combination with a printing press embodying a jogger board, a plurality of traveling tapes and inking rollers located adjacent to said tapes, of a casing disposed 85 between said tapes and provided with a plurality of openings, a plurality of nozzles arranged around said jogger board and communicating with said casing, and a rotary fan for directing air from said casing and 90 discharging a portion thereof upon said inking rollers.

8. In combination with a printing press embodying a jogger board, a plurality of traveling tapes and inking rollers located 95 adjacent to said tapes, of a casing disposed between said tapes, a plurality of nozzles arranged around the jogger board and communicating with said casing, a suction fan located adjacent to said tapes and communicating 100 with the interior of said casing, a spray device supported by the casing in a direction to discharge air upon said inking rollers, a pipe establishing communication between the spray device and the exhaust 105 of the fan and a valve controlling the exhaust of the fan to thereby control the air passing through said pipes to the spray device.

In testimony whereof I affix my signature. 110

JACOB FRANKLIN FREDERICK.
